SUSPENSION UNIT FOR CHAIR BACKS

Walter F. Herold, Bridgeport, Conn., assignor to
The General Fireproofing Company, Youngs-
town, Ohio, a corporation of Ohio

Application November 15, 1937, Serial No. 174,712

14 Claims. (Cl. 155—164)

This invention relates to chair irons or chair hardware used for supporting the seats and backs of swivel chairs.

One of the objects of the invention is to provide a novel unit for supporting or suspending and also adjusting the angular position of the back of the chair relative to the seat. In that connection the invention contemplates a novel construction which lends itself to standard manufacturing practices, is economical to manufacture, and easy to install and operate.

A special object of the invention is to provide a unit of the character set forth including novel rubber cushioning means which will yield when the chair back is rocked rearwardly on its suspending pivot. In that connection the rubber cushioning element may be provided with finger or hand engaging means to facilitate its manipulation and adjustment.

20 A further object of the invention is to provide a novel cushioning unit including an internally threaded member which cooperates with a relatively fixed screw member thereby to hold the parts in adjusted position.

25 With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings in which:

Figure 1 is a top plan view of a portion of a chair iron illustrating the details of the present improvement.

Figure 2 is a vertical sectional view of the construction shown in Figure 1, the adjusting unit being shown in elevation.

40 Figure 3 is a vertical sectional view taken on the line 3—3 of Figure 1.

Figure 4 is a detail horizontal sectional view taken on the line 4—4 of Figure 2.

Figure 5 is a vertical sectional view taken on the line 5—5 of Figure 3.

Figure 6 is a vertical sectional view taken on the line 6—6 of Figure 3.

Figure 7 is an elevation illustrating a modification of the invention.

50 Figure 8 is a detail sectional view of the modification shown in Figure 7.

Similar reference characters designate corresponding parts throughout the several figures of the drawings.

55 The chair iron designated generally as C pref-

erably includes the frame parts C¹ and C² which are secured to the underside of the chair seat in the conventional way and are intended to support and mount the seat on a suitable support generally as T, and which also includes 5 the swivel mounting S.

The back supporting unit of the present invention is designated generally as B and is carried by the rear of the chair iron C as will be apparent from Figures 1 and 2. Said member 10 B includes in its organization a plate 1 secured by the fastenings 2 to the chair iron parts C¹ and C², the said plate in turn being connected by the fastenings 3, and the intermediate washers 3a, if required, with the web 4 of an 15 inverted U-shaped bracket having the depending side walls 5—5. The side walls 5—5 are provided at their upper rear corners with the pivot ears 6 for receiving a pivot bolt 7 from which the part 8 of a guide bracket G is rock- 20 ably or pivotally supported.

The part 8 includes a front wall 9 which is notched or slotted as indicated at 10, while the edges of the part 8 opposite the wall 9 are formed with the guide flanges 11—11. These flanges 25 are intended to cooperate with the inturned guide flanges 12—12 of a mating guide part 13 carried by the transverse strap 14 of the back and which in turn supports the uprights of the chair back at opposite ends. It will, therefore, 30 be apparent that the transverse strap or member 14 which carries the back of the chair may be vertically adjusted through the medium of the interengaging guide flanges 11 and 12. For the purpose of locking or setting the adjustable element 14 in a selected position, a locking screw 35 15 may be employed. The said screw 15 is mounted in a threaded support 16 carried by the inside face of one of the side walls of the part 8 and its front end 17 is intended to wedg- 40 ingly engage a portion of one of the flanges 11 and the inner face of the member 13.

Thus, the back structure is vertically adjustable on the guide means G and the latter is pivotally or rockably supported on the trans- 45 verse pivot bolt 7 so that the angular position of the back structure relative to the seat may be readily varied by a novel adjusting unit designated generally as E.

The said adjusting unit E includes a threaded member or screw 19 which is fixedly supported at one end in the vertical leg of an angular bracket 20 rigidly fastened to the opposite side walls 5—5 of the main support. The said threaded member is rigidly held in place by 50 55

the nut 21 and the nut 22, and is disposed in a horizontal direction and below the pivot 7 on which the guide bracket G is intended to rock. The threaded member 19 is engaged by an internally threaded sleeve 23, externally flanged at one end as indicated at 24, while the opposite end carries rigidly therewith a disc 25 which is, therefore, rotatable with the sleeve along the threads of the member 19.

10 A rubber cushioning element 26, having a central bore 27 for loosely fitting over the sleeve 23, and also having a knurled or equivalent finger gripping bead 28 is held or clamped between the disc 25 and a second disc 29. This disc 29 abuts against the shoulder 29a on the sleeve, and, thus, the disc 25, cushion 26, and disc 29 all turn with the sleeve.

15 On the portion of the sleeve between the flange 24 and shoulder 29a, there is mounted a block 30 which is free to turn on the sleeve. As will be apparent from Figures 4 and 5 the block 30 is grooved at opposite sides as indicated at 31 to provide guides for receiving the side edges of the wall 9 at the slot 10 therein. Said guide formations 31 of the block 30 are each made with opposite knife edge portions 32 and 33 thereby to provide ample clearance for the varying angular positions of the guide bracket G on the pivot.

20 As the sleeve 23—24, discs 25 and 29 and rubber cushioning element 26 may readily turn on the threaded member 19, it will be apparent that the flange 24 of the sleeve will compel the block 30 to follow their movement. In this way, that is, by manually turning the rubber cushion element 30, the bracket G may be rocked on its pivot 7 to control the angular position of the back supported thereby.

25 If the back including the parts 12, 13 and 14 is pushed rearwardly, as for instance by the occupant of the chair leaning backwardly, the washer or disc 29 will be moved away from shoulder 29a and block 30 will move away from flange 24 to compress the rubber cushion 26 against the disc 25. Thus, the back of the chair will yield due to the rubber cushion 26. When pressure is relieved from the back of the chair the rubber cushion will push the washer 29 and block 30 back to normal position.

30 The sleeve 23, discs 25 and 29 together with the cushion member 26 constitute a nut-like member operating on the screw 19 and loosely connected with the bracket G. The relative adjustment between the nut-like member and the screw does not vary the compression on the cushion 26. In Fig. 3 the cushion 26 is not initially compressed. If it is desired to vary the compression of the cushion, suitable means may be provided as shown in the modified form of construction shown in Figs. 7 and 8. In any case, however, the degree of compression is not changed by the relative adjustment of the bracket to the support.

35 A modification of the invention is illustrated in Figures 7 and 8 wherein the rubber cushion element may be compressed to the desired degree by the user of the chair, as distinguished from the relatively non-compressed cushion in Figures 1—6. The modified adjusting unit E' is preferably carried at one end by a bracket 35 mounted on the underside of the chair seat S' which is suitably supported in any conventional manner to swivel or turn.

40 The screw, or threaded member 19a, is rigidly supported at its forward end in the bracket by the washer 21a and clamping nut 22a. Mounted

on the screw 19a is an internally threaded sleeve 23a having a shoulder 29a and a flange 24a at one end while the opposite end is externally threaded as indicated at 23b, to receive the internally threaded upset portion 36 of a novel compressor disc 37.

45 Said disc is provided with a flange 38 which houses a circular bearing ring or wear shim 39 having an offset annular rib 40 for engaging the inside face of the disc 37. The purpose of the rib 40 is to provide a small area of contact between the inside face of the disc 37 and the wear ring 39 when the compressor disc 37 is rotated on the threads 23b, thereby to render turning of the disc 37 easier, and preventing direct contact between the compressor disc and the rubber cushion element 41. Said cushion element is arranged between the ring 39 and the opposite disc 42 held against the shoulder 29a of the sleeve. Moreover, the cushion member 41 (preferably rubber) is provided with a bore to fit over the upset portion 36 of the disc 37 and also to fit over and clear the external surface of the sleeve 23a as well as the threads 23b.

50 Externally the cushion element 41 is provided with a knurled or equivalent bead or ring 43 to facilitate the manual rotation of the entire unit E' which consists of the cushion 41 and discs 37 and 42 together with the wear plate or shim 39 clamped between the compressor disc 37 and the cushion element 41. Since the disc 42 abuts against the shoulder 29a of the sleeve, and thus cannot move in one direction, it will be apparent that by rotating the disc 37 on the threads 23b of the sleeve it will be possible to compress the cushion element 41 to the desired degree, through, of course, the medium of the wear ring or shim 39.

55 The sleeve 23a carries between the disc 42, which abuts against the shoulder 29a, and the flange 24a a suitable block 44 which is provided externally with the guide flanges 45 whose inner faces are formed after the fashion of knife edges to engage the opposite side edges of the slot or notch 10a in the wall 9a of the bracket G'. This bracket carries the back of the chair and is pivotally supported or hung from the transverse pivot 7a in the same manner as the bracket G.

60 According to this embodiment of the invention it will be apparent that the cushion element 41 may be compressed to the desired degree at will to cause the back of the chair to encounter more or less resistance as it is rocked on the suspending pivot 7.

65 From the foregoing it will be apparent that the present invention provides a rockably supported or suspended bracket for carrying the back of the chair and that the angular adjustment of the back is effected through a novel adjusting unit arranged below the point of pivotal connection between the bracket G and the support B, the said unit including means for cushioning the back in one direction when it is subjected to pressure. The adjusting unit, therefore, performs the dual function of adjusting and cushioning the back of the chair.

70 Without further description it is thought that the features and advantages of the invention will be readily apparent to those skilled in the art, and it will, of course, be understood that changes in the form, proportion and minor details of construction may be resorted to, without departing from the spirit of the invention and scope of the appended claims.

75 I claim:

1. A mounting for chair backs including a pair of pivotally connected members, one of which carries the chair back, extensible and contractible threaded connection means between said members including a rotatable part, means slidably connected to said rotatable part and pivotally connected to one of said members, said rotatable part adapted upon rotation in one or the other directions to extend or contract said connection means to adjust the angular relation of said members about said pivot, and cushioning means carried by and rotatable with said rotatable part and arranged to be engaged by said slidable means for axial compression whereby pivotal movement between said members is cushioned in one direction. 5
2. A mounting for chair backs including a pair of pivotally connected members, one of which carries the chair back, extensible and contractible threaded connection means between said members including a rotatable part, means slidably connected to said rotatable part and pivotally connected to one of said members, said rotatable part adapted upon rotation in one or the other directions to extend or contract said connection means to adjust the angular relation of said members about said pivot, and a rubber cushioning body carried by said rotatable part in co-axial relation therewith and having an exposed peripheral surface for the manual turning of said rotatable part, said cushioning body being arranged to be engaged by said slidable means for axial compression whereby pivotal movement between said members is cushioned in 10 one direction. 30
3. A mounting for chair backs including a pair of pivotally connected members, one of which carries the chair back, extensible and contractible threaded connection means between said members including a threaded shaft part connected to one of said members, and a threaded nut part engaged with said shaft part and connected to the other of said members, one of said parts being rotatable in one or the other directions to extend or contract said connection means to adjust the angular relation of said members about said pivot, and cushioning means carried by said nut part, said cushioning means being arranged between a rigid portion of said nut part, and means slidably and pivotally connecting the nut part with the other of said members whereby pivotal movement between said members is cushioned in one direction by axial compression of said cushioning means. 40
4. A mounting for chair backs, including, a support, and a bracket carrying the chair back, a pivot rockably suspending the bracket from the support, and means for adjusting the bracket relative to the support, said means including a threaded member secured to the support, an internally threaded sleeve rotatably mounted on the threaded member, said sleeve having fixed and movable abutments thereon, a cushion member carried by and rotatable with said sleeve and arranged between said abutments, and means pivotally connected with the bracket and slidably connected with the sleeve and having a portion bearing against the movable abutment whereby pivotal movement of said bracket in one direction will axially compress the cushion member. 45
5. A mounting for chair backs including a support, a bracket for carrying the chair back, a horizontal pivot rockably suspending the bracket from the support, and a combined adjusting and cushioning unit, said unit including a threaded member secured at one end in the support, an internally threaded sleeve mounted on said threaded member and having an abutment flange at one end; a disc rigidly carried by the other end of the sleeve, another disc loosely mounted on said sleeve, means on the sleeve between said last mentioned disc and said abutment flange pivotally engaging said bracket, and a rubber cushioning unit having a central bore for receiving said sleeve and arranged between said discs. 50
6. A mounting for chair backs including a support, a bracket for carrying the chair back including a notched wall portion, a horizontal pivot rockably suspending the bracket from the support, and an adjusting unit for controlling the angular relation of the bracket relative to the support, said unit including a threaded member secured at one end to said support, a sleeve having a shoulder and internally threaded to travel on said threaded member, a flange at one end of the sleeve, a disc fixed to the end of the sleeve opposite the flange, another disc loosely fitting over the exterior of the sleeve and abutting said shoulder, a block on the sleeve between said shoulder and flange, pivoting guide means at opposite sides of said block for loosely engaging in the notch of said fixed wall of the bracket, and a rubber cushion member arranged between said discs. 55
7. A mounting for chair backs including a pair of pivotally connected members, one of which carries the chair back, rotatable adjusting means for changing the angular relation of said members about said pivot, said means including an externally threaded element carried by one of said members, an internally threaded rotatable sleeve including means pivotally engaged with the other of said members and adapted to travel on said externally threaded element, and cushioning means arranged between a portion of said sleeve and one of said members whereby arcuate movement between said members is cushioned in one direction. 60
8. In combination, a pair of pivotally connected members, one of which members carries a chair back, and means for adjustably setting and holding said members in selected angular position, said means comprising a threaded element carried by one of the members, a sleeve having rigid abutments one of which is a disc and the other of which is a shoulder, said sleeve being internally threaded to engage and travel on said threaded element, a second disc slidably arranged on the sleeve and engaging said shoulder, a flange on the end of the sleeve, a block slidably on the sleeve between said flange and said last mentioned disc and pivotally interlocked with one of said pivotally connected members, and a rubber cushion mounted on the sleeve between said discs. 65
9. In a mounting for chair backs, a support, a bracket carrying the back and pivoted to said support, and means for adjusting the angular position of said bracket, said means including a threaded member fixed at one end to the support and having means at its opposite end pivotally interconnected with said bracket, a sleeve having a shoulder and internally threaded for adjustment along said threaded member, a pair of spaced discs one of which is rigidly mounted on the external surface of said sleeve and the other of which is free to move on the sleeve but normally engaged with the shoulder thereon, and 70

- a cushion element arranged between said discs.
10. In a mounting for chair backs, a support, a bracket carrying the back and pivoted to said support and means for adjusting the angular position of said bracket, said means including a threaded member fixed at one end to the support and having means at its opposite end pivotally interconnected with said bracket, a sleeve having a shoulder and internally threaded for adjustment along said threaded member, said sleeve also having an externally threaded portion, a pair of spaced discs, one of which is rotatably mounted on the externally threaded portion of the sleeve and the other of which is free to move on the sleeve but normally engaged with the shoulder thereon, and a cushion element confined between said discs.
11. In a mounting for chair backs, a support, a bracket carrying the back and pivoted to said support and means for adjusting the angular position of said bracket, said means including a threaded member fixed at one end to the support and having means at its opposite end pivotally interconnected with said bracket, a sleeve having a shoulder and internally threaded for adjustment along said threaded member and also provided with an externally threaded portion opposite said shoulder, a disc loosely engaging the sleeve but abutting said shoulder, a rubber cushion fitted over said sleeve, a wear ring fitted against one side of the cushion, and a flanged disc having a central opening in threaded engagement with the externally threaded portion of the sleeve to be adjustable thereon with reference to the first mentioned disc to compress the rubber cushion, said last mentioned disc bearing against the wear ring and having its flanged portion roughened for finger engagement and manipulation.
12. In a mounting for chair backs, a support, a bracket carrying the back and pivoted to said support, and means for adjusting the angular position of said bracket, said means includ-

ing a threaded member fixed at one end to the support and having means at its opposite end pivotally interconnected with said bracket, a sleeve thereon and internally threaded for adjustment along said threaded member, a pair of discs mounted on the external portion of said sleeve, a cushion element arranged between said discs, one of said discs engaging means fixed on the sleeve to prevent movement in one direction and the other of said discs being adjustable back and forth relative to said first disc to vary the compression of said cushion element.

13. In a mounting for chair backs, a support, a bracket pivoted to the support for carrying the back, and means for adjusting the angular position of said bracket, said means comprising, a threaded member rigidly carried at one end by the support, and an adjusting unit mounted on said threaded member, and pivotally interlocked at one end with the pivoted bracket, said adjusting unit including a sleeve internally threaded and engaging said screw threaded member, and also having a portion thereof externally threaded and provided with a shoulder, a disc mounted loosely on the exterior of said sleeve to about said shoulder, a wear ring having a rib on one face thereof, a flanged disc having a central portion internally threaded for engaging with said external threads of the sleeve, and the inside face of said flanged disc engaging said rib on the wear ring, and a cushion element fitting over said sleeve and arranged between the first mentioned disc and said wear ring.

14. In a mounting for chair backs, a support, a bracket pivoted to the support for carrying the back, an adjustable unit including means for setting and holding said back in a selected adjusted angular position, means between said first named means and said bracket adapted to yield when pressure is applied in one direction to the chair back, and adjustment means arranged to vary the yieldability of said last named means.

WALTER F. HEROLD.
